(57) **CLAIM**

The ornamental design for a portable electric sander, as shown and described.

DESCRIPTION

FIG. 1 is a front perspective view of a portable electric sander in accordance with our new design;

FIG. 2 is a rear perspective view of the portable electric sander in accordance with our new design;

FIG. 3 is a front elevational view of the portable electric sander in accordance with our new design;

FIG. 4 is a rear elevational view of the portable electric sander in accordance with our new design;

FIG. 5 is a top plan view of the portable electric sander in accordance with our new design;

FIG. 6 is a bottom plan view of the portable electric sander in accordance with our new design;

FIG. 7 is a right side elevational view of the portable electric sander in accordance with our new design;

FIG. 8 is a left side elevational view of the portable electric sander in accordance with our new design; and,

FIG. 9 is a front perspective view, similar to FIG. 1, of the portable electric sander in accordance with our new design illustrating a state in which a sandpaper attachment, a battery and a side handle are attached to the portable electric sander. The broken line showing of the sandpaper attachment, the battery and the side handle in FIG. 9 is provided for the purpose of illustrating environmental structures; whereas the broken line showing in FIGS. 1-8 illustrates portions of the portable electric sander. These broken line subject matters do not form part of the claimed design.

1 Claim, 9 Drawing Sheets
